UNITED STATES PATENT OFFICE

JACOB J. KAGAN, OF LOS ANGELES, CALIFORNIA

DESIGN FOR A FINGER RING

Application filed October 11, 1932. Serial No. 45,314. Term of patent 14 years.

To all whom it may concern:

Be it known that I, JACOB J. KAGAN, a citizen of the United States, and a resident of the city of Los Angeles, in the county of Los Angeles and State of California, have invented a new, original, and ornamental Design for a Finger Ring, of which the following is a specification, reference being had to the accompanying drawing, forming part thereof, in which—

The figure is a perspective view of a finger

ring showing my new design, it being understood that the side obscured from view shows the same motif as that of the side shown.

The dominant feature of the design resides in the interwoven effect of a number of strands that are exposed on the exterior of the ring.

I claim:

The ornamental design for a finger ring substantially as shown and described.

JACOB J. KAGAN.
